(54) **WHEELS, SPOKES FOR**

(76) Inventor: **Daniel H. Wiswell**

The Schedule referred to in these letters Patent, and making part of the same, containing a description in the words of the said Daniel H. Wigwalt himself of his improvement being a machine for making spokes for wheels.

Be it known, that I, Daniel H. Wigwalt, of Pittsfield, in the County of Berkshire, and State of Mass-achusetts, have made an improvement in the useful art, being a machine for making spokes for wheels, which is described as follows:-

This machine consists of the following principal parts: viz:- The frame, which supports and encloses the machinery; the wheel for cutting the timber, and the wheel for rounding the edges of the spoke; the carriage and rack which carries the spoke to the wheel for rounding the edges; the arbor with the spiral worm which works in the rack of the carriage; the weights or spring for drawing back the carriage; circular levers for keeping the timber; and the gearings by which the machinery is moved.

The frame is adapted in size and strength to the machinery to be enclosed and supported; and is constructed by uniting and turning together, about six parts, four side pieces or girths, two end pieces and a girth or cross piece.

The wheel for cutting the timber is made of cast iron, about 15 inches diameter, with a groove in the edge of it to receive four or more cutters.

The wheel for shaping the edges of the spoke, is of the same size as the before described, having also four or more cutters, of the figure, slope, or inclination of the front of the spoke. When the front and back of the spoke are regarded to be made of different timber, then another wheel is added, with a similar groove, to receive cutters for rounding the back of the spoke to the figure required; or an additional groove may be made in the wheel before described for that purpose; the wheel in that case must be made larger.

The circular levers for keeping the timber for the spokes are placed parallel to each other and upon the same arbor or arbor which turns the spoke bending wheels.

The carriage, and rack which carries the spoke to the wheel to be shaped is placed below the before mentioned wheels. The carriage is moved by an arbor with a spiral screw or worm and working into the rack on the outside of the carriage. The same arbor turns with one end upon a small bearing in a pin or part, the other end of which is attached a lever for moving it up and down, easily to the other end of the arbor with the end below the carriage. The other end turns in a bearing, upon a small wheel placed on the frame, and the end of the arbor upon a bearing sufficiently far from the carriage to allow the carriage to move up and down, without the arbor being turned.

supports the driver for putting it in and out of gear. A small pin on the side of the carriage lets off the spring-tight which allows the end of the team to be let down, and then it is out of gear, and by pushing down the large mounted spur attached to the carriage, it is raised, and the team is put in gear. —

A spoke attached to a end, pointing outwards, and fastened to the carriage, brings it back again, when the operation of dipping, the spoke is performed. —

The gear: A kind of a battole is having a groove in it is fixed near the end of the one end, supported on the frame. On its arbor is a small wheel working into the track for one end placed on the arbor which carries the spiral saw working into the rock. A wheel is placed on the end of the axle which carries the dipping saws and the cutters, and a band goes round the wheel and that which drives the arbor for moving the rock. Motion is given to the machinery by the hand or any other power. —

Operation: The timber for the spoke is first shaped to its proper thickness by the circular saw: the iron is then formed by the cutters in the groove of the turner cutting wheel. The spoke is then rounded and placed upon the carriage; one end resting against a pin, and supported by a wedge; and so turned that the other: when the front edges are shaped by the cutters it is turned and the back edges shaped either by the same arbor, or others put upon another wheel, when intended to be of a different thickness and shape. —

The invention here claimed and desired to be secured by letters Patent consists of the whole system before described machine, when taken together, particularly the wheel of cutters for shaping the edges of the spoke: — but no claim is made to circular saws, the gear, turning wheel and other parts before described taken separately.

For a further distinction of my invention, I refer to the model and drawing of the same deposited in the Patent Office.

I inventing whereof, have herunto subjoined my name this 6th day of April 1833.
